PLATE OR SIMILAR ARTICLE

John H. Reiser, Downey, Calif.
(P.O. Box 47, Huntington Park, Calif.)

Filed Dec. 5, 1960, Ser. No. 63,120

Term of patent 14 years

(Cl. D44—15)

The figure is a plan view of a plate of conventional configuration, showing my new design.

The section of motif shown is continued around the entire circumference of the plate.

I claim,

The ornamental design for a plate or similar article, substantially as shown and described.
